(57) CLAIM

The ornamental design for a wide angle rear view mirror, as shown and described.

DESCRIPTION

FIG. 1 is a top plan view of a wide angle rear view mirror showing my new design, the bottom plan view is substantially a mirror image of that shown;

FIG. 2 is a side elevational view thereof;

FIG. 3 is an opposite side elevational view thereof; and,
FIG. 4 is a front elevational view thereof, the rear view is substantially a mirror image of that shown.
